PLUG RECEPTACLE

Filed Aug. 24, 1928

UNITED STATES PATENT OFFICE

FREDERIC P. GATES, OF WEST HARTFORD, CONNECTICUT, ASSIGNOR, BY MESNE ASSIGNMENTS, TO THE ARROW-HART & HEGEMAN ELECTRIC COMPANY, OF HARTFORD, CONNECTICUT, A CORPORATION OF CONNECTICUT

PLUG RECEPTACLE

Application filed August 24, 1928. Serial No. 301,745.

This invention relates to an attachment plug for power devices such as electric ranges, and hereinafter termed "a load" or "loads" and more particularly to providing ground-
5 ing means in the plug for the power device.

An object of the invention, therefore, is to provide an attachment plug having ground-
ing means therein.

Another object of the invention is to pro-
10 vide grounding means for a power device, through the intermediary of a novel type of attachment plug.

Other objects will appear hereinafter.

In the drawing in which is illustrated one
15 form of my invention:

Fig. 1 is a perspective view of the cap portion of the attachment plug;

Fig. 2 is a perspective view of the base portion;

20 Fig. 3 is a vertical section through the assembled device;

Fig. 4 is a view taken on line 4—4 of Fig. 3;

Fig. 5 is a view taken on line 5—5 of Fig. 3,
25 looking in the direction of the arrows;

Fig. 6 is a view taken on line 6—6 of Fig. 3,
looking in the direction of the arrows; and

Fig. 7 is a detail section taken on line 7—7
of Fig. 6.

30 As will be seen, the plug in the present in-
stance is wired for a three wire system, al-
though the invention is susceptible to use in
any types of circuits, and is provided in the
base with contact clips 1, 2, 3 and 4; clips 1,
35 2 and 3 being contacted to or formed integral-
ly with hollow lugs 5, 6, and 7, by means of
which the clips are attached to outlet leads.
It will be seen that clip 4 is unattached to
any lug, but is directly attached, as is evident

40 from Fig. 3, to the supporting strap 8 which
has upturned legs 9, terminating in outward-
ly extending flanges 10. These flanges 10
may be provided with holes 11 for the recep-
tion of screws, bolts or other form of clamp-
45 ing means. It is obvious that the exact shape

of the supporting strap may be varied at will
without departing from the spirit of the in-
vention.

As seen in Fig. 3, the base comprises a bot-
tom section 12 on which the clips are snugly 50
seated in depressions, and a co-operating top
member 13, also provided with longitudinal
channels 14, 15, 16 and 17, adapted to receive
blades 18, 19, 20 and 21.

The above-mentioned blades are preferably 55
contained in a two part cap having a top
portion 22 and a bottom portion 23. The
top portion 22 may be centrally bored as at
24 to receive the metal-sheathed cable 25, in
which are contained the three leading-inwires 60
26, 27 and 28. These wires are received in
lug elements 29, 30 and 31, formed on the
ends of clips 18, 19 and 20.

Around the cap portion of the plug is a
retaining strap comprised of metal strips 32 65
and 33. These straps each conform to the
shape of the cap and are preferably dia-
metrically opposed. At their upper ends
they terminate in semi-circular yokes 34 and
35 having wings thereon for the reception of 70
securing means, such as screws or bolts 36.

The side walls and bottom face of lower
section 23 are preferably cut away as at 37
and 38 to receive the inturned flanges 39 and
40 of the straps 32 and 33. 75

These straps in their preferred form are
provided with slots 41 and 42, which cooper-
ate with recesses 43 and 44 in the top section
22 of the cap, for the reception of screws
or bolts 45 and 46, by means of which the two 80
portions 22 and 23, and the straps 32 and 33
are secured together, the screws 45 and 46
extending through the flanges 39 and 40 of
the strap.

The contact blade 21 is integrally formed 85
as a downturned continuation of flange 39.

As will be seen from Fig. 3, the clip 4 is
electrically and mechanically attached to the
supporting strap 8 by suitable means such as
the screw 47. 90

The two sections 12 and 13 may be secured together by means of screws 48 and 49.

As will be readily apparent, when the plug is assembled, the blades 18, 19, 20 and 21 contact with clips 1, 2, 3 and 4, the frame of the power device, having been connected to the supporting strap 9, will be grounded by means of a circuit through 9, and thence through bolt 47, clip 4, blade 21, flange 39, strip 32, yoke 34 and cable 25 back to the power source.

In this way an efficient and positive grounding means is easily and simply supplied, the only connections required being to attach the supporting strap of the plug to the power or load device.

Numerous modifications will be apparent to those skilled in the art, and it is intended that the scope of the invention be limited only by the appended claims.

I claim:

1. A two part connector comprising a plug and a receptacle, a clip carried by said receptacle, means for electrically connecting said clip to an article to be grounded, a metallic strip extending partly around the exterior of said plug, said strip having a contact blade at one end which removably contacts with said clip, said metallic strip being adapted to be grounded at its other end.

2. A two part connector comprising a plug and a receptacle, a clip carried by said receptacle, means for electrically connecting said clip to an article to be grounded, a plurality of opposed strips arranged around the exterior of said plug and serving to embracingly hold the parts thereof together, at least one of said strips being metallic, the metallic strip having a contact blade at one end which removably contacts with said clip, said metallic strip being adapted to be grounded at its other end.

3. A two part connector comprising an attachment plug and socket having a strap around one part, said strap being adapted for electrical connection with an article to be grounded, said strap being electrically connected with a clip in said part which it surrounds, a plurality of opposed strips arranged around the exterior of the other part at least one of said strips being metallic, the metallic strip having a contact blade, which removably contacts with said clip, said metallic strip being adapted to be grounded at its other end.

4. A two part connector comprising an attachment plug and receptacle having a strap around one part thereof adapted for electrical connection with an article to be grounded, four contact clips in said one part, three of which are connected to outlet leads and the fourth of which is electrically connected to said strap, the other part of the connector having four contact blades, three of which blades are connected at one end to leading-in

wires contained in a metallic sheath and removably contacting at the other end with said three clips, the other of said blades removably contacting at the other end to said fourth clip, and a plurality of opposed strips arranged around the exterior of said last-mentioned part at least one of said strips being metallic, the single contact blade being formed on one end of the metallic strip and the other end of the strip being electrically connected to the metallic sheath, thus completing a ground connection.

FREDERIC P. GATES.
